[57] CLAIM

The ornamental design for a fireplace grate, as shown and described.

DESCRIPTION

FIG. 1 is a perspective view of a fireplace grate embodying my new design.

FIG. 2 is a right side elevational view thereof, the left side being the same as the side shown;

FIG. 3 is a front elevational view thereof, the rear being the same as the front shown;

FIG. 4 is a top plan view thereof;

FIG. 5 is a bottom plan view thereof;

FIG. 6 is a perspective view of a modified form of the fireplace grate shown in FIG. 1; and

FIG. 7 is a right side elevational view of FIG. 6, the left side being the same as the side shown.
